UNITED STATES PATENT OFFICE.

LOUIS WOJIDKOW, OF BROOKLYN, NEW YORK, ASSIGNOR TO NEW YORK STAMPING COMPANY, OF BROOKLYN, NEW YORK, A CORPORATION OF NEW YORK.

STOPPER FOR RECEPTACLES.

1,045,100.

Specification of Letters Patent. Patented Nov. 19, 1912.

Application filed May 31, 1912. Serial No. 700,868.

To all whom it may concern:

Be it known that I, LOUIS WOJIDKOW, a citizen of the United States, residing at Brooklyn, in the county of Kings and State 5 of New York, have invented a certain new and useful Improvement in Stoppers for Receptacles, of which the following is a full, clear, and exact description.

The object of this invention is to provide 10 a screw stopper for receptacles of various kinds. Such screw stoppers are oftentimes anchored to the receptacles by means of a chain, and as these stoppers are screwed into place the chain becomes fouled or twisted 15 and thereby the operation of the stopper is obstructed.

A feature of the present invention is to so connect the chain with the stopper proper 20 that the chain will not be fouled or twisted in the operation of the stopper.

The invention consists of a screw stopper 25 having a laterally extended finger or sweep, such as an L-shaped piece, preferably swiveled in it, and this finger is connected with the chain which in turn has its other end anchored in some portion of the receptacle.

In illustration of the invention, I have shown it applied to a hot water plate, the 30 novel features of which form the subject of an application for patent of even date herewith, but obviously the invention is not limited to this single use, and the hot water plate is merely selected as illustrative of one application of the invention.

In the accompanying drawings illustrating 35 the invention, in the two figures of which like parts are similarly designated, Figure 1 is a top plan view of a hot water plate supplied with my stopper, the stopper being removed and drawn at one side. Fig. 40 2 is a transverse section, on a larger scale, showing a portion of the plate and its filling and pouring spout supplied with the stopper of this invention.

1 may indicate the metal portion of the 45 hot water plate, and 2 a ceramic top portion thereof, and 3 the detachable plate-holding flange connecting the plate 2 and the body portion 1 in a detachable manner. 50 4 is the filling and pouring spout. 5 are the handles, and 6 the handle-securing devices, all substantially as in the construction set forth in the application referred to.

As shown, the cover plate 7 of the filling

and pouring spout has a collar 8 screw-threaded internally. The stopper 9 has an interior flange 10 screwthreaded externally to engage the screwthreaded collar 8, and it also has an outside flange 11 which may be knurled or otherwise constructed 60 to afford a finger-hold for the operator in turning it into and out of place on the collar 8. 12 is an L-shaped piece, herein referred to as the laterally extended finger or sweep. This finger preferably is swiveled at 13 in the stopper 9, so as to permit the stopper to turn freely, and having secured at its free end one end of any suitable anchoring chain or other device 14, whose other end is attached to the receptacle. 70

As the stopper is screwed to place, the finger 12 may turn with it, but it could never foul or become tangled with the chain 14, because its free end extends sufficiently far in a lateral direction to hold the chain off 75 from entanglement with it. The swiveling of the finger in the stopper aids in securing this result.

Obviously the gist of the invention here 80 is the provision of a finger projecting laterally from the stopper to such an extent as to prevent the chain from being fouled or twisted in turning the stopper into and out of place, and whether the said finger be swiveled in the stopper or otherwise connected with it to effect the object stated.

What I claim is:

1. A stopper for receptacles, adapted to be turned into place, combined with an anchoring medium, and a member extending laterally from the stopper and connecting it with the anchoring medium and adapted to prevent the fouling or twisting of the anchoring medium in turning the stopper into and out of place. 90

2. A stopper for receptacles, comprising a screw cap having a laterally extended finger swiveled therein, and an anchoring medium fixed to the outer end of the finger by one end and adapted to be secured in the 100 receptacle by the other end.

In testimony whereof I have hereunto set my hand this 29th day of May A. D. 1912.

LOUIS WOJIDKOW.
